(74) Attorney, Agent, or Firm—Arthur J. Hansmann

(57) **CLAIM**

The ornamental design for a screwdriver handle, as shown and described.

DESCRIPTION

FIG. 1 is a side perspective view of one embodiment of a handle showing my new design;

FIG. 2 is a top plan view thereof, the bottom view being identical thereto;

FIG. 3 is a right side elevation view, the left side elevation view being a mirror image thereof;

FIG. 4 is a rear elevation view thereof;

FIG. 5 is a front elevation view thereof;

FIGS. 6 and 7 are section views taken respectively on the lines 6—6 and 7—7 of FIG. 3.

FIG. 8 is a side perspective view of another embodiment of a handle showing my new design;

FIG. 9 is a top plan view thereof, the bottom view being identical thereto;

FIG. 10 is a right side elevation view, the left side elevation view being a mirror image thereof;

FIG. 11 is a rear elevation view thereof seen in FIG. 10;

FIG. 12 is a front elevation view thereof seen in FIG. 10; and,

FIGS. 13 and 14 are section views taken respectively on the lines 13—13 and 14—14 of FIG. 10.
